UNITED STATES PATENT OFFICE.

CHARLES B. GARRETT, OF MINNEAPOLIS, MINNESOTA, ASSIGNOR, BY DIRECT AND MESNE ASSIGNMENTS, TO THE GLOBE AUTOMATIC SPRINKLER COMPANY, OF MINNEAPOLIS, MINNESOTA, A CORPORATION OF MINNESOTA.

DRY-PIPE VALVE.

No. 831,054.

Specification of Letters Patent.

Patented Sept. 18, 1906.

Application filed Oct. 3, 1903. Serial No. 175,552.

To all whom it may concern:

Be it known that I, CHARLES B. GARRETT, a citizen of the United States, residing at Minneapolis, in the county of Hennepin and State of Minnesota, have invented certain new and useful Improvements in Dry-Pipe Valves; and I do hereby declare the following to be a full, clear, and exact description of the invention, such as will enable others skilled in the art to which it appertains to make and use the same.

My present invention has for especial object to provide an improved dry-pipe valve for use in connection with so-called "dry-pipe fire-extinguishing systems;" and to this end it consists of the novel devices and combinations of devices hereinafter described, and defined in the claims.

The invention is illustrated in the accompanying drawings, wherein—

Figure 1 is a vertical section taken centrally through a dry-pipe valve embodying the several features of my invention. Fig. 2 is a horizontal section on the line $x^3 x^2$ of Fig. 1. Fig. 3 is a plan view of the lower portion of the valve mechanism, all that part above the line $x^3 x^3$ of Fig. 1 being removed. Fig. 4 is a bottom plan view of the so-called "secondary" or air valve, and Fig. 5 is a section taken approximately on the line $x^5 x^5$ of Fig. 4.

Like characters indicate like parts throughout the several views.

The body 1 of the valve case or shell is provided with three valve-seat-equipped openings 2, 3, and 4. The valve-seat 2, which constitutes a water-inlet passage, is located in the bottom of the case or shell 1 and is in communication with a branch 5 of the street-main, or other source of water-supply under pressure. The valve-seat 3, which affords the water outlet from the casing 1, is located in an inclined upper wall 1^a of said casing and opens into the main riser 6, the lower portion of which is expanded and is detachably secured to the casing 1 by a water-tight joint, as shown, extending on the line $x^3 x^3$ of Fig. 1. The valve-seat 4 is located in one side of the casing 1 and serves a purpose which will hereinafter appear. The valve-seats 2, 3, and 4 are adapted to be closed by valves which may be treated, respectively, as the primary or water-inlet valve, the sec-

ondary or air-seated valve, and the intermediate or vent-closing valve.

The primary valve 7 is carried by an arm 8, 55 fulcrumed to a bearing 9, rigidly secured to and within the casing 1, adjacent to the valve-seat 2. Advisably, the valve 7 is provided with a nutted stem 10, that works loosely through the arm 8, and the arm 8 is provided with a plurality (as shown four) of set-screws 11, that press upon the valve 7 and hold the same firmly seated on the valve-seat 2, when the free end of the arm 8 is pressed downward.

The secondary valve 12 is carried by and has a slight pivotal movement on an arm 13, pivoted to the bearing 14, rigidly secured on top of the casing 1 in such position that said valve 12 will normally rest upon the valve-seat 3. On its under face the valve 12 is provided with a slidable cam-block 15, the base of which, as shown, works in a groove 16, formed in said valve 12. The cam-block 15 has a threaded stem 17, that works loosely through a pair of lugs 18 on the said valve 12, and a thumb-nut 19 works on said stem 17 between said lugs 18, to adjust said cam-block 15 and hold the same in any desired set position.

A tripping-lever 20 is pivoted at its lower end to a bearing-bracket 21, secured to and within the casing 1, at the right-hand side of the primary valve 7, as viewed in Fig. 1. The free upper end of this tripping-arm 20 terminates at such point that it will engage the cam-block 15 of the secondary or air valve 12, when said valve is in a closed position. The tripping-arm 20 is further provided with a presser-heel 22, (as shown cast integral therewith,) that normally presses upon the free end of the arm 8 and holds the primary valve 7 closed. Furthermore, this tripping-arm 20 carries the so-called "intermediate" or "vent-closing" valve 23, which valve, as shown, is pivoted thereto and is attached to one end of a chain 24. The chain 24 passes the air-vent afforded by the valve-seat 4, runs over a sheave 25, mounted on the bracket 26 on the exterior of the casing 1, and is provided at its depending end with a headed rod 27. A plurality of weights 28, placed on the headed rod 27, puts the tripping-arm 20 under a strain which tends to open the sec-

ondary or air-seated valve 12, and to close the intermediate or vent valve 23, all as will hereinafter more fully be described.

Working through a suitable stuffing-box 29 in the side of the casing 1 is a circuit-closing plunger 30, the inner end of which stands in position to be engaged by the free end of the tripping-arm 20 when the latter is moved into a position to force the intermediate valve 23 against its valve-seat 4, as indicated by dotted lines in Fig. 1. The plunger 30 acts upon the circuit-closer 31, which cooperates with contacts 32 of an annunciator-actuating circuit 33, which circuit further includes a battery 35^a and an electric bell 33^b.

The numeral 34 indicates a valved drain-pipe for draining the system after operation and as preliminary to setting the valve mechanism for action, and the numeral 35 indicates a valved priming-pipe which opens into the expanded lower portion of the main riser 6.

Operation: With the parts set in normal position, as indicated by full lines in Fig. 1, it is evident that when the air-pressure in the riser 6 is sufficiently reduced the weights 28, acting through the chain 24 on the tripping-lever 20, will open the secondary valve 12 and force the vent-valve 23 against the valve-seat or vent 4, thereby closing the latter, and that such actions will take place independent of any action of the primary valve. Otherwise stated, the said secondary valve will be opened and the vent will be closed, even though the water-pressure should be cut off from the branch 5 of the water-main, in which case, of course, the primary valve 7 not being subject to water-pressure would remain closed. Furthermore, the above-noted operative movement of the tripping-lever 20 under the action of the weights 28 will force outward the plunger 30 and cause the circuit-closer 31 to close the annunciator-circuit, and thus give notice that the dry-pipe has been thrown into action by the reduction of the air-pressure in the main riser 6, due to the rupturing of one or more of the sprinkler-heads. The tripping-lever 20 must move in order to actuate the alarm, and it must also move to close the vent-opening 4. In moving to close the vent the tripping-arm 55 will open or unseat the secondary valve 12, while the vent 4 is still open. It is desirable to have the vent open at the time the secondary valve is open in order to relieve the latter from suction or back pressure. Furthermore, it is desirable to open the secondary valve and close the vent, even though there should be no pressure on the primary or water-supply valve 7, as this sets the mechanism for action whenever such pressure is applied to the said primary valve, and, in fact, sets the mechanism of the dry-pipe valve so that water might be supplied to the casing 1 by means independent of the water-supply pipe 5.

In the present design the proportions of the primary and secondary valves are such as to produce a tripping of the valves at about ten pounds of air when the water-pressure in the pipe 5 is at approximately 70 one hundred pounds per square inch, the said relations, therefore, being about ten to one.

The weights 28 preferably are such that independent of the influence of the water-pressure on the primary valve 7 they will 75 open the secondary valve 12 and close the vent 23 at from three to five pounds of air-pressure in the riser 6. Thus the tripping-point will be further raised, say, one pound more, but varying according to the tension 80 put upon the tripping-lever under different adjustments of the cam-block 15. This will set the valve mechanism for tripping at a point between fourteen to eighteen pounds of air-pressure when the water-pressure is 85 at one hundred pounds. By bringing the weights 28 or other device used for putting the tripping-lever under strain to the exterior of the casing convenient access thereto is had, so that the valve mechanism may at 90 be adjusted to trip into action at any desired pressure within certain limits. This feature is therefore important.

By locating the face of the valve-seat 3 at an oblique angle to the periphery of the 95 valve-seat 2 and by pivoting the tripping-lever at one side of said valve-seat 2 the free end of said tripping-lever is arranged to act on the cam-block 15 in a direction approximately tangential to the face of the secondary valve 12 and causing the free end of said lever to act upon the cam-block 15 with a sweeping action quickly opens the said valve.

To afford access to the interior of the casing 1 for the purpose of resetting the valve and the tripping-lever, said casing is shown as provided with a detachable plate 36.

By adjusting the cam-block 15 on the secondary valve 12 the valve-closing strain on the tripping-lever 20 may be varied to some extent, and by adjustments of the set-screws 11 of the valve-arm 8 the said tripping-lever may be set so that its free end will fall within the range of adjustment of the said 115 cam-block.

To reset the valve mechanism after it has been thrown into action or when it is first installed, the water is drawn off from the system by opening the valve in the drain-pipe 34, and the said drain-valve is then closed. Then the plate 36 is removed to afford access to the interior of the casing 1. Next the primary valve is turned down into a closed position and then the weights 28 being removed from the rod 27 the tripping-lever 20 is turned to its normal position. Next the secondary valve 12 is turned downward into a closed position and the annunciator-actuating plunger 30 is pressed in 130

ward. Then after priming the chamber of the main riser just above the secondary valve the air is turned on through the said main riser and the secondary valve will then 5 of course be held seated. After this has been done the weights 28 are again applied to the rod 27 and the valve mechanism is then again set for automatic action whenever the predetermined pressure of air in the 10 riser 6 takes place.

From the foregoing description and statements made it will of course be understood that the valve mechanism described is capable of many modifications as to details of 15 construction within the scope of my invention as herein set forth and claimed.

What I claim, and desire to secure by Letters Patent of the United States, is as follows:

1. In a dry-pipe valve, a casing or shell 20 forming part of the conduit of a fire-extinguishing system and having three openings, three valves operating to open and close said three openings, and mechanism operatively connecting said three valves, but permitting 25 simultaneous actions of two of said valves, independent of the action of the said third valve.

2. In a dry-pipe valve, a casing or shell 30 forming a part of the conduit of a fire-extinguishing system, and having three openings, three valves operating to open and close said three openings, mechanism within said casing, operatively connecting said three valves, but permitting simultaneous action of two of 35 said valves independent of any action of the third valve, and means exteriorly accessible for regulating the pressure under which certain of said valves will be normally seated, substantially as described.

40 3. In a dry-pipe valve, the combination with a casing forming a part of the conduit of a fire-extinguishing system and having a water-inlet, a water-outlet, and an air-vent, of a primary valve normally closing said water- 45 inlet, a secondary air-seated valve normally closing said outlet, a third valve coöperating with said air-vent, and mechanism operatively connecting said three valves, and operating to simultaneously open said secondary valve and close said air-vent valve, independent of the action of said primary valve.

4. In a dry-pipe valve, the combination with a casing forming a part of the conduit of a fire-extinguishing system and having three 55 openings, of three valves, two of which normally close two of said openings and the other valve being movable to close the one of said openings, and mechanism operatively connecting said valves and operating to simultaneously open one of said valves and close said normally open valve, independent of the action of the third valve.

5. The combination with a casing forming part of the conduit of a fire-extinguishing 60 system, said casing having a water-inlet, a

water-outlet and an air-vent, primary and secondary valves normally closing said inlet and outlet, respectively, a third valve which normally opens but is movable to close said air-vent, and means operatively connecting 70 said three valves and operating to open said secondary valve and close said vent-valve, independent of the action of said primary valve.

6. In a dry-pipe valve, the combination 75 with a primary valve normally holding back the water-supply, of a secondary air-seated valve normally closing the water-outlet, an air-vent in said casing an oscillating tripping-lever for opening said secondary valve and 80 for normally holding said primary valve closed, and a vent - closing valve carried by said tripping-lever, the movement of which tripping-lever serves to open said secondary valve and close said vent-valve, independent 85 of the action of said primary valve.

7. The combination with a casing forming part of the conduit of a fire-extinguishing system, said casing having an inlet and an outlet and an air-vent, of primary and secondary valves normally closing said inlet and outlet, respectively, a normally open vent-closing valve having a pressure-actuated connection extending through said air-vent, to the exterior of said casing, and valve-actuating 90 mechanism connecting said three valves and operating to open said secondary valve and close said air-vent valve, independent of the action of said primary valve.

8. The combination with a casing forming 100 part of the conduit of a fire-extinguishing system, said casing having a valved water-inlet, a valved water-outlet and an air-vent, of a tripping-lever for opening the outlet-valve, and normally holding said inlet-valve 105 closed, of a third valve independent of the other two valves carried by said tripping-lever and adapted to be moved to close said air-vent, under that movement of said tripping-lever which opens said outlet-valve, and 110 means for producing such movement of said tripping-lever, involving a connection extended through said air-vent to the exterior of said casing.

9. The combination with a casing forming 115 part of the conduit of a fire-extinguishing system, and having a water-inlet, a water-outlet and an air-vent, of an inlet-valve and outlet-valve normally closing said inlet and outlet respectively, an air - chamber into 120 which said secondary valve opens, and whereby it is air-seated, a tripping-lever for opening said outlet-valve and normally holding said inlet-valve closed, and a third valve independent of said other two valves, carried 125 by said tripping-lever and adapted to be moved to close said air-vent, under that movement of said tripping-lever which opens said secondary valve, substantially as described.

- 4
10. The combination with a casing forming part of the conduit of a fire-extinguishing system, said casing having a water-inlet, a water-outlet leading to an air-chamber, and an air-vent leading to the atmosphere, of a primary valve normally closing said inlet and holding back the water-supply, an air-seated secondary valve normally closing said water-outlet, a normally open third valve for closing said air-vent, and mechanism operatively connecting said three valves, but causing said secondary valve to open, and said vent-valve to close, independent of the action of said primary valve.
15. The combination with a casing forming part of the conduit of a fire-extinguishing system, said casing having a water-inlet, a water-outlet and an air-vent, of primary and secondary valves normally closing said inlet and outlet, respectively, a normally open vent-closing valve, an adjustable weight attached to said vent-valve by a connection passed through said air-vent, and valve-actuating mechanism connecting said three valves, and operating under the action of said weight, to open said secondary valve and close said vent-valve, independent of the action of said primary valve.
20. The combination with a casing forming part of the conduit of a fire-extinguishing system, said casing having a water-inlet, a water-outlet, and an air-vent, primary and secondary valves normally closing said inlet and outlet, respectively, a tripping-lever for opening said secondary valve and normally holding said primary valve closed, a vent-closing valve carried by said tripping-lever, and a connection from said tripping-lever extended outward through said vent and provided with a weight, the strain of which weight will open said secondary valve and close said vent-valve, independent of the action of said primary valve.
25. The combination with a casing forming part of the conduit of a fire-extinguishing system, said casing having a water-inlet and a water-outlet, of primary and secondary valves normally closing said inlet and outlet, respectively, an arm carrying said primary valve and adjustably connected therewith, an adjustable cam-rod on said secondary valve, and a tripping-lever acting on said cam-block to open said secondary valve and acting on the adjustable lever of said primary valve, to hold said primary valve closed, the said tripping-lever being normally under strain tending to open said secondary valve, substantially as described.
30. The combination with a casing forming part of the conduit of a fire-extinguishing system, said casing having a water-inlet, a water-outlet, and an air-vent, primary and secondary valves normally closing said inlet and outlet, respectively, a tripping-lever for opening said secondary valve and normally holding said primary valve closed, a vent-closing valve carried by said tripping-lever, and a connection from said tripping-lever extended outward through said vent and provided with a weight, the strain of which weight will open said secondary valve and close said vent-valve, independent of the action of said primary valve.
35. The combination with a casing forming part of the conduit of a fire-extinguishing system and having a water-inlet and a wa-
- ter-outlet, of primary and secondary valves normally closing said inlet and outlets, respectively, an adjustable cam-block mounted on said secondary valve, a tripping-lever engageable with said cam-block, to open said secondary valve, and operating to normally hold said primary valve closed, and means putting said tripping-lever under strain to open said secondary valve and release said primary valve.
40. The combination with a casing forming part of the conduit of a fire-extinguishing system, said casing having water inlet and outlet passages equipped with valve-seats which valve-seats lie in planes diverging at an oblique angle, of a tripping-lever pivoted at one side of said water-inlet, primary and secondary valves normally closing said inlet and outlet, respectively, and means causing said tripping-lever to normally hold said primary valve closed, and for causing the same to open said secondary valve when the latter is relieved from pressure, substantially as described.
45. The combination with a casing forming part of the conduit of a fire-extinguishing system, said casing having a water-inlet and a water-outlet, of primary and secondary valves normally closing said inlet and outlet, respectively, an arm carrying said primary valve and adjustably connected therewith, an adjustable cam-rod on said secondary valve, and a tripping-lever acting on said cam-block to open said secondary valve and acting on the adjustable lever of said primary valve, to hold said primary valve closed, the said tripping-lever being normally under strain tending to open said secondary valve, substantially as described.

In testimony whereof I affix my signature in presence of two witnesses.

CHARLES B. GARRETT
